UNITED STATES PATENT OFFICE.

EUGENE L. PERRY, OF WARREN, PENNSYLVANIA.

COPY-HOLDER.

1,256,253.

Specification of Letters Patent. Patented Feb. 12, 1918.

Application filed January 15, 1917. Serial No. 142,436.

To all whom it may concern:

Be it known that I, EUGENE L. PERRY, a citizen of the United States, residing at Warren, in the county of Warren and State 5 of Pennsylvania, have invented certain new and useful Improvements in Copy-Holders, of which the following is a specification.

The general object of my invention is to provide a stenographer's note-book holder 10 and line-indicator which will be simple in construction and thoroughly efficient in operation.

Another object of the invention is to provide a structure of the kind stated, whereby 15 the line-guide or indicator may be moved step by step by novel mechanism, and with a maximum of ease and celerity.

Another object of the invention is to provide simple, reliable and conveniently ad- 20 justed mechanism whereby the line-indicator may be moved a greater or lesser distance, at each step, as may be desired, to accord with the differing spacing between the lines in various note-books and copy.

Another object is to provide a note-book 25 holder, or copy-holder, the parts of which will not be liable to get out of order; and, moreover, a device which will be compact in its organization and which will present 30 a slightly and attractive appearance.

Another object is to provide a note-book holder which may be manufactured at a reasonable cost.

Another object is to provide a note-book 35 holder in which the slide, carrying the line-indicator or guide, is reliably retained in position by frictional means permitting it to be moved with ease when desired.

Another object is to provide a mechanism 40 wherein the slide, carrying the line-indicator or guide, may be moved step by step by a frictional clutch operated by a finger-lever, and wherein said slide may be manually rectilinearly moved in reverse directions, irre- 45 spective of said clutch.

Other objects and features of the invention will appear as the specification proceeds and the nature of the invention more fully appears.

50 In the accompanying drawings forming part of my specification and in which like reference characters denote corresponding parts throughout the several views, there is disclosed on illustratory exemplification of

one form of embodiment capable of carry- 55 ing out the underlying principles of the invention. The several views may be briefly described as follows:

Figure 1 is a perspective view of a note- 60 book holder embodying my invention;

Fig. 2 is a fragmentary rear view, partly in section, of the holder;

Fig. 3 is a detached detail perspective view of the slide carrying the line-indicator or guide; 65

Fig. 4 is a view in side elevation, partly in section, of the holder, looking at the left-hand side of the holder shown in Fig. 1;

Fig. 5 is a fragmentary front elevation of 70 the holder;

Fig. 6 is a sectional view, on the line 6—6 of Fig. 5, looking in the direction of the arrows;

Fig. 7 is a horizontal sectional view on the line 7—7 of Fig. 6, looking in the direction 75 of the arrows; and

Fig. 8 is a horizontal sectional view on the line 8—8 of Fig. 6, looking in the direction of the arrows.

Referring, now, in detail to the drawings: 80

1 designates the book-shelf or rest, which is, preferably, a plate, as shown, provided, desirably, with rearward-extending side flanges 2, 2 (one of said flanges being shown in the drawing, it being understood that 85 there is a similar flange on the other side of the book-rest), and with a bottom flange 3, hook-shaped in cross-section, constituting a seat for the book or copy A. The form of the book-rest may, however, be changed. 90

A clamp of suitable form is provided for the upper part of the book or sheets A upon the support 1. In this instance the clamp preferably comprises a rod having an arm 4 extending transversely of the front face 95 of the book-rest, and having, also, an arched portion 4' adjacent one side thereof, and a second arm 4^a extending transversely across the rear face of the book-rest and pivotally mounted in the side flanges 2 thereof. The 100 arched connecting portion 4' offsets the arm 4 from and parallel with the pivot of the clamp, so that the clamping arm swings upward to clear the copy rest. A spring 5 coiled around the arm 4^a, and having one 105 terminal 5' bearing against the book-rest 1 and the other terminal 5^a secured to said arm, operates to maintain the arm 4 in

clamping position against the copy and to return it to clamping position after it has been manually lifted so as to place copy in position on or withdraw it from the book-rest.

Carried toward and parallel with one side of the book-rest 1, and disposed on the upper surface thereof, is a slide-track or slide-guide. An advantageous construction for 10 this track or guide is one in which it takes the form of a board open channel having the body or base 6 thereof resting on the upper surface of the book-rest 1 and preferably riveted thereto, as shown at 7, and having the longitudinal, upturned flanges 6', 6'.

Movable in a rectilinear path on said track is a slide, which is shown as comprising a broad elongated channel member 9, of slightly less width than the channel guide 20 6 and having its side flanges 9, 9' facing in the reverse direction to the flanges 6', 6', against which and against the upper surface of the base of the track 6 the said flanges 9, 9' have their sliding bearing. This particular preferred construction of the guide and slide, while simple and not costly, is strong and especially efficient in operation and presents a good appearance. Carried by said track 6, some distance from the top 25 30 thereof, is a boss 8, constituting a slide-stop.

The slide carries two rearward-projecting fingers 10, 10, desirably formed by slitting and bending up a portion of the material of the slide (which is preferably of 35 sheet metal). One of these fingers 10 (that toward the upper end of the slide) contacts with the stop 8, in the downward movement of the slide, and thus limits downward movement thereof, and the other finger 10 40 (that toward the lower end of said slide) contacts with the stop 8 when the slide is pushed upward, so as to limit upward movement thereof, as is obvious. The slide is movable in the guide beyond the upper end 45 of the copy support.

Said slide 9 carries, toward the lower end thereof, an arm or shaft 11 extending transversely thereof and of the book-rest 1. A line indicator blade 12 is pivoted along its 50 lower edge region upon this arm, so that it may be tilted upward and forward about the arm as an axis away from the copy. This movement of the line indicator is effected by means of a finger-piece 13 projecting 55 from the lower or pivotal portion of the blade away from the plane of the copy support. The finger-piece, it will be noted, is located adjacent the slide, for which reason it may be used not only to tilt the 60 line indicator when desired but also to move the indicator and slide upward to starting position after the completion of a page.

A frictional device is provided capable 65 of arresting and holding the slide at any position. Such means may be varied, but pref-

erably comprises two arms 14, 14 projecting loosely through slots in the book-rest 1, being united with a base 15 disposed beneath said book-rest and with terminal lips 16, 16, bearing upon the upper surface of 70 the slide 9, the whole constituting a species of sleeve bodily movable transversely to the plane of the book-rest. To maintain the top of this sleeve in frictional clamping contact with the slide 16, suitable means are 75 provided, in this instance a coil-spring 17 interposed between the under surface of the book-rest 1 and the base 15 of the clamping member, and tending to push or press the base away from the book-rest 1 and consequently the part 16, 16 toward and against the slide 9. This friction device not only serves to hold the slide against shifting lengthwise, but also to keep the slide in the open guide, against dislodgment. 80

The preferred form of mechanism for moving the line-indicator 12 in a step-by-step manner and through variable distances will now be described.

A bell-crank lever 18 is fulcrumed at 19 90 on a bracket 20 carried at one side by the book-rest 1, or otherwise, the free extremity of the longer arm thereof being conveniently provided with a finger-piece 21 toward the lower end of the rest, and the extremity of 95 the shorter arm being pivotally connected with a link 22, whose other end is pivotally connected with one end of a friction-clutch member, comprising an arm 23 working in an opening 24 in the book-rest 1, and formed 100 to receive one side portion of the channel slide 9. The arm 23 may consist of a bar formed with a longitudinally-extending slot 31, in which is accommodated one of the flanges 9' of the slide 9, and with a transverse slot 32 extending from the inner side face of the arm 23 and merging into the longitudinal slot 31, in which slot 32 the body portion of the slide 9 is accommodated. Secured to the arm 23, near its slide-engaging portion, is one end of a retractile 110 spring 26, the other end whereof is secured to one of the side flanges 2 of the book-rest.

In operation, by depressing the finger-piece 21, the lever 18 is rocked on its fulcrum, so as to draw downward the link 22, which at first tilts the arm 23 slightly so as to grip or bind the top wall of the slide between the extremity 25 and the inner jaw 33, after which the clutch and slide are 120 pulled downward and forward to the extent determined by an adjustable limit stop, presently to be described. As soon as the finger-piece 21 is released, the arm 23 and the lever 18 are returned idly to normal position by the spring 26, while the slide 9 is held in position by the friction sleeve as described. 125

My invention contemplates an adjustable stop for limiting downward movement of 130

the arm 25, when the lever 18 is rocked by the operator. In this instance said stop is a longitudinal rod 27 threaded at its lower end, as shown at 28, and engaging the 5 threaded aperture of a bearing 29 carried at the lower end of the book-rest 1. The lower end of the rod 27 may rigidly carry a knurled head 30, for conveniently rotating the same to change the position of its upper 10 end, which is in the path of movement of the arm 23. By thus moving said end nearer to or farther from the normal position of the clutch, the extent of the individual line-spacing movements may be regulated.

15 The upper portion of the rod 27 may pass through a pin 33 (as shown in Fig. 2) which in turn passes desirably through a textile pad 34, or the like, interposed between the rod 27 and the flange 2. The pin 33 is exteriorly threaded and projects through the flange 2, and a set-nut seated on the exteriorly-projecting end of said pin serves to tighten up the pin to press the rod 25 27 against the pad 34, thus constituting a frictional guide for the rod.

20 The outer side portion and flange 6' of the track 6 is preferably cut away from the point *a* to the point *b* to accommodate the clutch, and the shoulder *b* may constitute a stop (as shown in Fig. 4) to limit upward movement of the arm 23, under the influence of the spring 26.

25 In this copy-holder, it will be perceived, the book or copy-rest is stationary and the line-indicator and its simple operating mechanism are all that require to be shifted by the typist through the key 21 to cause the indicator to follow the lines. When the indicator reaches the lower end of the rest, the page is completed, and may be removed from the holder, or the page of the book turned, upon releasing the clamp 4. The indicator may now be quickly moved to the 40 top again by grasping and pushing upward upon *a* the finger-piece 13. In this movement the slide is not gripped by the clutch and slides freely, with little resistance, in the holding sleeve. By placing the transverse 45 line-indicator at the lower end of the longitudinal slide 9, the latter does not at any time project materially below or in front of the body of the rest.

50 The copy-holder above described may be supported in different ways, either vertically or at an inclination, and in various positions with respect to the typewriting machine. One desirable mode of support comprises a stable pedestal 37 which may be placed as 55 desired upon the desk, and to the upper end of which the body 1 of the rest is tiltably connected by a frictional hinge joint 38, which permits the copy to be held at any angle from the horizontal to practically a vertical position.

Having thus fully described my invention, the many advantages thereof will be apparent, especially to those skilled in the art to which it pertains.

I am aware that changes, especially in detail, may be made in the physical embodiment of the invention described and illustrated; and it will be understood that all such changes and modifications coming within the scope of the claims are within the 75 purview of my invention.

What I claim as new is:

1. In a copy-holder, a copy-support, a longitudinal-channel slide movable on said support, and a clutch engageable with said slide 80 to move the same step by step, and having a longitudinal slot receiving one of the side flanges of said slide, and a transverse slot into which the body portion of said slide projects.

2. In a copy-holder, a copy-support, a longitudinal-channel slide movable on said support, a clutch engageable with said slide to move the same step by step and having a longitudinal slot receiving one of the side 90 flanges of said slide and a transverse slot into which the body portion of said slide projects, and means for automatically releasing said clutch from said slide after movement of the clutch to engage and move said 95 slide.

3. In a copy-holder, a copy-support, a longitudinal-channel slide movable on said support, a clutch engageable with said slide to move the same step by step and having a 100 longitudinal slot receiving one of the side flanges of said slide and a transverse slot into which the body portion of said slide projects, and means for frictionally holding said slide on said support, including a 105 spring-pressed member loosely projecting through the support and bearing on said slide.

4. In a copy-holder, the combination of a copy support, a longitudinal guide carried 110 thereby at one side of the copy-receiving surface, an elongated slide mounted on the guide and movable thereon beyond the end of the copy support, a line indicator extending transversely from the slide, a tilt-able clutch located at one region and formed 115 with an opening whereby it is adapted to embrace the slide at any point along its length and to cramp thereon when tilted, a key and operating connections connected 120 to the clutch in such manner as to tilt and pull it downward toward the lower end of the copy-holder, means for regulating the extent of such movement of translation of the clutch, a spring connected with the 125 clutch in such manner as to retract it freely along the stationary slide, and a friction device for holding the slide against shifting.

5. In a copy-holder, the combination of a copy support, a longitudinal guide carried 130

- thereby at one side of the copy-receiving surface, an elongated slide mounted on the guide and movable thereon beyond the end of the copy support, a line indicator extending transversely from the slide, a tilttable clutch located at one region and formed with an opening whereby it is adapted to embrace the slide at any point along its length and to cramp thereon when tilted, a bell-crank 5 key-lever mounted on a lower side portion of the copy support, a pull link connecting the key-lever with the clutch in such manner as to tilt and pull the clutch downward, means for regulating the extent of such 10 movement of translation of the clutch, a spring connected with the clutch in such manner as to retract it freely along the stationary slide, and a friction device for holding the slide against shifting.
- 15 6. In a copy-holder, the combination of a copy support, a longitudinal guide carried thereby at one side of the copy-receiving surface, a broad elongated slide mounted on the guide and movable thereon beyond the end of the copy support, a line indicator extending transversely from the slide, a tilttable clutch located at one region and adapted to cramp upon the slide when tilted, means for 20 tilting the clutch and moving it downward toward the lower end of the copy-holder, a spring connected with the clutch in such manner as to retract it freely along the stationary slide, and a friction device for holding the slide against shifting.
- 25 7. In a copy-holder, the combination of a copy support, a longitudinal broad open channel guide carried by the support at one side of the copy-receiving surface, a broad elongated slide fitted in the guide and movable thereon beyond the end of the copy support, a line indicator extending transversely from the slide, a tilttable clutch located at one region and adapted to cramp upon the slide when tilted, means for 30 tilting the clutch and moving it downward toward the lower end of the copy-holder, a spring connected with the clutch in such manner as to retract it freely along the stationary slide, and a friction device for holding the slide against shifting.
- 35 8. In a copy-holder, the combination of a copy support, a broad longitudinal channel guide carried by said support at one side of the copy-receiving surface, a broad elongated channel slide movable on the guide beyond the end of the copy support, a line indicator extending transversely from the slide, a tilttable clutch located at one region and formed with an opening whereby it is 40 adapted to embrace the slide at any point along its length and to cramp thereon when tilted, the channel guide being cut away at one side at said region to permit the clutch to act upon the slide, a key and operating connections connected to the clutch in such manner as to tilt and pull it downward toward the lower end of the copy-holder, means for regulating the extent of such 45 movement of translation of the clutch, a spring connected with the clutch in such manner as to retract it freely along the stationary slide, and a friction device for holding the slide against shifting.
- 50 9. In a copy-holder, the combination of a copy support, a longitudinal guide carried thereby at one side of the copy-receiving surface, an elongated slide mounted on the guide and movable thereon beyond the upper end of the copy support, a line indicator extending transversely from the slide substantially at its lower end, a tilttable clutch located at one region and adapted to cramp upon the slide when tilted, means for 55 tilting the clutch and moving it downward toward the lower end of the copy-holder, a spring connected with the clutch in such manner as to retract it freely along the stationary slide, and a friction device for holding the slide against shifting.
- 60 10. In a copy-holder, the combination of a copy support, a longitudinal broad open channel guide carried by the support at one side of the copy-receiving surface, a broad elongated slide fitted in the guide and movable thereon beyond the end of the copy support, a line indicator extending transversely from the slide, a tilttable clutch located at one region and adapted to cramp upon the slide when tilted, means for 65 tilting the clutch and moving it downward toward the lower end of the copy-holder, a spring connected with the clutch in such manner as to retract it freely along the stationary slide, a sleeve surrounding the guide and slide and occupying an opening in the copy support, and a spring pressing the sleeve to bear frictionally upon the slide.
- 70 11. In a copy-holder, the combination of a copy support, a longitudinal guide carried thereby at one side of the copy-receiving surface, an elongated slide mounted on the guide and movable thereon beyond the end of the copy support, an arm projecting laterally from the slide, a line indicator blade pivoted along its lower edge on said arm so as to be tilttable away from the copy, a finger-piece on the lower portion of said blade adjacent the slide serving both for 75 tilting the blade and for moving the blade and slide upward, a tilttable clutch located 80
- 85 12. In a copy-holder, the combination of a copy support, a longitudinal guide carried thereby at one side of the copy-receiving surface, an elongated slide mounted on the guide and movable thereon beyond the end of the copy support, a line indicator extending transversely from the slide, a tilttable clutch located at one region and adapted to cramp upon the slide when tilted, means for 90 tilting the clutch and moving it downward toward the lower end of the copy-holder, a spring connected with the clutch in such manner as to retract it freely along the stationary slide, a sleeve surrounding the guide and slide and occupying an opening in the copy support, and a spring pressing the sleeve to bear frictionally upon the slide.
- 95 13. In a copy-holder, the combination of a copy support, a longitudinal guide carried thereby at one side of the copy-receiving surface, an elongated slide mounted on the guide and movable thereon beyond the end of the copy support, a line indicator extending transversely from the slide, a tilttable clutch located at one region and adapted to cramp upon the slide when tilted, means for 100 tilting the clutch and moving it downward toward the lower end of the copy-holder, a spring connected with the clutch in such manner as to retract it freely along the stationary slide, a sleeve surrounding the guide and slide and bearing upon the top of the latter, and a spring pressing the sleeve so as to hold the slide both against dislodgment from the open guide and against shifting longitudinally thereon.
- 105 14. In a copy-holder, the combination of a copy support, a longitudinal guide carried thereby at one side of the copy-receiving surface, an elongated slide mounted on the guide and movable thereon beyond the end of the copy support, an arm projecting laterally from the slide, a line indicator blade pivoted along its lower edge on said arm so as to be tilttable away from the copy, a finger-piece on the lower portion of said blade adjacent the slide serving both for 110 tilting the blade and for moving the blade and slide upward, a tilttable clutch located 115
- 120 15. In a copy-holder, the combination of a copy support, a longitudinal guide carried thereby at one side of the copy-receiving surface, an elongated slide mounted on the guide and movable thereon beyond the end of the copy support, an arm projecting laterally from the slide, a line indicator blade pivoted along its lower edge on said arm so as to be tilttable away from the copy, a finger-piece on the lower portion of said blade adjacent the slide serving both for 125 tilting the blade and for moving the blade and slide upward, a tilttable clutch located 130

at one region and adapted to cramp upon the slide when tilted, means for tilting the clutch and moving it downward toward the lower end of the copy-holder, and a spring connected with the clutch in such manner as to retract it freely along the stationary slide.

In testimony whereof I affix my signature in the presence of two witnesses.
